BOTTLE HOLDER AND LOCK

William H. Wallace, Jacksonville, Fla., assignor
of one-third to Louis W. Anderson, Jacksonville, Fla., and one-third to Charles S. Wallace, Morehead City, N. C.

Application January 11, 1939, Serial No. 250,418

2 Claims. (Cl. 232—41)

This invention relates to devices for receiving and preventing the theft of portable receptacles, and more particularly to devices for receiving milk bottles and maintaining them within a lock.

Prior devices, while they are capable of receiving portable receptacles and generally maintaining them in locked position, are of such nature that they do not provide positive protection against theft, for in most cases the bottles may readily be removed by picking the lock with an ordinary thin instrument. Such prior devices having locks which may not so easily be opened by the unauthorized have been unduly complicated and expensive to manufacture.

It is an object of this invention to provide a simple device which will receive a portable receptacle and maintain the same in locked position.

It is a further object of the invention to provide a device of the nature which lends itself to ready and inexpensive manufacture, and capable of holding a milk bottle within a simple lock which may not be readily tampered with by the unauthorized.

Other objects and the nature and advantages of the invention will be apparent from the following description taken in conjunction with the accompanying drawing, wherein:

Fig. 1 is a longitudinal cross section of my device, showing the milk bottles retained in place;

Fig. 2 is also a longitudinal cross section, showing the milk bottles entering my device;

Fig. 3 is a longitudinal cross section showing the bottle about to be retained;

Fig. 4 shows a transverse section of my device;

Fig. 5 illustrates a front end elevation;

Fig. 6 is a view similar to Fig. 5 showing a modification of my invention in which the filler blocks are eliminated;

Fig. 7 is a longitudinal cross section, showing a further modification of my invention; and,

Fig. 8 is an end elevation of the modification shown in Fig. 7.

Referring to the drawing, a channel shaped member 10 is provided with projecting edges 11 and a central upfolded portion 12, defining a relatively narrow space. This member is made of a comparatively rigid metal, preferably a sheet iron stamping which has been galvanized or otherwise treated to prevent rusting. The inturned edges 11 of the channel shaped member 10 are designed of such size as to grip the upper bead of the ordinary milk bottle and hold the bottle supported by the bead. The member 10 may be

fastened to a door or window frame in either a horizontal or vertical position by means of wood screws or other securing means.

A latch member 13 is positioned within the upfolded central portion 12 of the member 10 and is horizontally pivoted on the pin or rivet 14. The member 13 has a bottle engaging portion 15 on the inner side of the pivot 14 and a cam shaped portion 16 on the outer or forward side of the pivot 14. A spring member 17 urges the inner end of member 13, which contains the bottle engaging portion, downwardly about the pivot 14.

As a milk bottle is entered into the guides formed by the inturned edges 11 of member 10 as shown in Fig. 2, there is sufficient clearance to allow the top of the bead on the bottle to pass under the cam 16 and slide inwardly on the guides. As the bottle progresses inwardly there is just sufficient clearance under the cam 16 to allow the bead at the forward top of the bottle to urge the front cam surface 15a of the bottle engaging portion 15 upwardly as shown in Fig. 3. As the bottle is pushed still further inwardly it reaches the position as shown in Fig. 1 in which the bottle engaging portion 15 of the member 13 is locked in front of the rear lip portion of the bottle. As clearly shown in Fig. 2, the cam portion 16 projects downwardly below the pivot 14, and when in its bottle-engaging position as shown in Fig. 1 the cam portion 16 also projects downwardly below the lip of the bottle and thereby prevents release of the latch by the insertion of an ordinary straight blade or strip beneath the latch, since the insertion of such a tool would cause the forward end 16 of the latch to be raised, thereby forcing the rear cam portion 15 deeper into the bottle.

The spring member 17 insures a positive locking of the bottle engaging portion 15 and aids in preventing the movement of the latch member 13 by insertion of a thin instrument beside the latch, as heretofore explained. As a still further precaution, the outward end 18 of the upfolded portion 12 of the member 10 is closed off by bending the edges 18 of this member together at their outward extremity.

Filler blocks 19 are provided, as shown in Fig. 4, to aid in securing my device to a flat surface; these blocks are preferably of wood but may be of other suitable material. Their function is as a spacer primarily, but also they add to the rigidity of the member 10. In the modification shown in Fig. 6 the filler blocks have been eliminated by providing the upwardly projecting portions 20

to directly engage the supporting surface. The central unfolded space 12 may be eliminated as shown in the second modification of my device as in Figs. 7 and 8. The modification of my device works in identically the same manner as the embodiment described, the only difference being in that in the modification shown in Figs. 7 and 8, the horizontal pivot 14 goes completely across the device and eliminates the central unfolded space.

It will be seen that I have provided a positive locking device for milk bottles in which the bottle may be inserted from the outside and pushed inwardly until engaged by the bottle engaging portion 15 of the member 13, at which time it is positively locked against removal from the outside. Since the inner end of this device is designed to be positioned against a door or window, the bottle may be removed only by opening the door or window. The door or window may be kept locked by the ordinary lock or fastening means provided, and unlocked and opened from the inside when it is desired to remove the bottle. The bottle may be removed by grasping it and pulling it inwardly through the guides. It should be understood that the member 10 together with the guides 11 may be made sufficiently long to provide for the reception of two or more bottles, as shown in Fig. 1. In that case, it is only necessary to locate one latch member 13 at the outer end of the device, since only the outer bottle need be engaged.

It will be obvious to those skilled in the art that various changes may be made in this device without departing from the spirit of the invention and therefore the invention is not limited

to what is shown in the drawing and described in the specification but only as indicated in the appended claims.

What is claimed is:

1. A milk bottle holder comprising an inverted channel member adapted to slidably receive the top portion of a milk bottle, said channel member having downwardly extending portions defining guides, a latch pivoted within said channel member between said guides, said latch having a bottle-engaging portion on the rearward side of its pivot and a cam portion on the opposite side of said pivot, said cam portion being formed to project downwardly below said pivot and below the lip of the bottle in its locked position in a manner to prevent the release of said bottle-engaging portion by the insertion of a straight strip or blade.

2. A milk bottle holder comprising an inverted channel member adapted to slidably receive the top portion of a milk bottle, said channel member having downwardly extending portions defining guides, and an elongated slot between said guides, a latch pivoted within said slot between said guides, said latch having a bottle-engaging portion on the rearward side of its pivot and a cam portion on the opposite side of said pivot, said cam portion being formed to project downwardly below said pivot and below the lip of the bottle in its locked position in a manner to prevent the release of said bottle-engaging portion by the insertion of a straight strip or blade, said slot being closed at its forward end to obstruct access to the top portion of said latch.

WILLIAM H. WALLACE.
